UNITED STATES PATENT OFFICE.

FRANK S. SEJNOHA, OF CHICAGO, ILLINOIS.

SMOKE-CONSUMER.

SPECIFICATION forming part of Letters Patent No. 520,453, dated May 29, 1894.

Application filed February 10, 1894. Serial No. 499,720. (No model.)

To all whom it may concern:

Be it known that I, FRANK S. SEJNOHA, a citizen of the United States, residing at Chicago, in the county of Cook and State of Illinois, have invented new and useful Improvements in Smoke-Consumers, of which the following is a specification.

This invention relates to smoke consumers, and its object is the production of a smoke consumer wherein a blast of air and steam is introduced into the furnace in such a manner as to act as a blanket whereby the solid particles of unconsumed matter and other products of combustion which are ordinarily carried off in the smoke from the combustion furnace are held in the combustion chamber until they are wholly consumed.

A further object is the production of a smoke consumer simple in construction, easily manipulated and efficient and effective in operation.

With these objects in view, the invention consists in the construction, arrangement, relative locations and adaptations hereinafter more particularly described, and as shown in the accompanying drawings, forming a part hereof, and finally pointed out in the appended claims.

Reference is now had to the accompanying drawings wherein similar reference signs indicate similar parts throughout the several views.

Figure 1 is a front elevation of a boiler with the invention applied thereto. Fig. 2 is a horizontal sectional view taken on the line 2—2 Fig. 1 looking in the direction of the arrows and showing a slightly different arrangement of the steam pipe. Fig. 3 is a vertical section taken on the line 3—3, Fig. 1, looking in the direction of the arrows. Fig. 4 is a view, in side elevation, looking from the rear, of the blast hood removed from its place in the brick setting of a furnace. Fig. 5 is a cross section taken on the line 5—5 of Fig. 4 and also showing in partial, longitudinal section, one of the air pipes feeding the blast hood. Fig. 6 is a longitudinal section of the steam nozzle, upon an enlarged scale.

A represents the brick work or setting of an ordinary furnace; B the bridge wall; C the grate bars; E the ash pit; F the ash-pit doors; G the furnace doors, all of the usual and well

known construction and therefore require no specific description.

H is a suitable steam pipe connecting at 55 one end in any suitable manner with the boiler, or other source of steam supply. I is a suitable stop cock located in said steam pipe for regulating the flow of steam therein. This pipe H forms a T-connection with 60 a short pipe K, centrally of the length thereof, and which said pipe is closed at the ends thereof as is clearly shown in Fig. 1. Projecting from this steam pipe K, are several short pipes each carrying at its end a nozzle 65 M. In the form shown in the drawings, see Figs. 1 and 2, two pipes L are arranged on each side of the T-connection between pipes H and K. Pipes L and nozzles M project a short distance into the mouth of larger pipes 70 N fitted or seated in the masonry or frame work of the furnace immediately above the furnace doors. The outer ends O of which see Figs. 2 and 5, project slightly beyond the frame work of the furnace and are open to 75 receive the outer air, as will be more fully hereinafter described. At the inner ends of these pipes N are formed elbows P. In the form shown in the drawings these pipes N are arranged in pairs, the elbows P of each pair 80 being turned toward each other.

Q represents the blast hoods, each hood swiveling upon a pair of elbows P so as to be capable of an angular adjustment thereupon for a purpose presently to be described. 85 A space in the framework or setting of the boiler immediately above the furnace door is provided for each hood Q so that when said hood is in place its nose, presently to be described, opens into the furnace chamber at a 90 point above the furnace door. This hood comprises an oblong hollow casing having the sides R, S and T thereof squared relatively to each other, and having the sides V and U beveled or inclined from the points b and a 95 respectively to the points c and d; the part from c to d forming a nose extending the whole length of the hood. This nose is slotted as at W, throughout its length, said slot communicating with the interior or chamber 100 of the blast hood. The bevel U is provided in order to secure a square bearing of the hood in its setting, and at the same time to permit the hood to be tilted upon its elbow supports P,

P, so as to adjust the nose and thus regulate and adjust the path of the blast through the furnace chamber as indicated by the arrows in Fig. 3.

5 Nozzle M is of simple construction and consists of a thimble or sleeve e internally screw threaded which is screwed onto the externally screw threaded end of pipe L.

10 f is the nozzle proper and is screwed into the thimble e as clearly shown in Fig. 6.

The pipes K are conveniently supported by brackets projecting from the front of the boiler or in any suitable and well known manner. These pipes are arranged conveniently 15 above the furnace doors and transverse of the furnace.

In the form shown in Fig. 1 pipe H leading from a convenient connection with the boiler or other source of steam supply is provided 20 with two elbows g and h and the leg below elbow h is located centrally of the furnace and extends vertically. If preferred however, the elbow h can be located immediately above the T-connection with pipe K and the 25 leg from elbows g to h extend horizontally immediately above pipe K to the side of the furnace, or any other convenient location and arrangement of said steam pipe H may be employed to adapt it to the construction 30 and arrangement of the furnace without departing from the spirit of my invention.

I have shown my invention as applied to a single furnace having double doors, but it is obvious that where several such furnaces are 35 employed, as is frequently the case in large factories, &c., arranged side by side, each furnace can be supplied with my invention. In such case each furnace may have a separate pipe H leading from or connected to its 40 own boiler, or else a single steam pipe can be arranged with connections from any one or more, or each of the boilers and the several pipes H may draw their steam supply therefrom or one pipe H may supply two adjacent 45 furnaces by a T-connection at the point where elbow g is now shown. In this latter case pipe K will be extended so as to receive a T connection centrally of the adjacent furnace similar in all respects to the T shown in 50 Figs. 1, 2 and 3, or else a separate pipe K can be provided for each furnace, as will be obvious. Again where a small furnace is employed having only one door to the furnace or combustion chamber, it is obvious that only 55 one blast hood need be employed. In that case only one pair of elbow pipes N and only one pair of pipes L and nozzles M need be employed, and the T-connection between pipes H and K can be located centrally between the 60 pair of pipes L as will be readily understood. Or if desired only one pipe L, nozzle M and tube N need be employed though I prefer two to each blast hood.

65 While I have shown the nose of the blast hood as provided with a slot or opening extending the whole length thereof, and while I prefer such construction, yet it is obvious

that I may have merely a series of perforations instead thereof or any other suitable connection may be made.

70 Many other variations and changes, all obvious to any person skilled in the art, may be made without departing from the spirit or scope of my invention, and I want it distinctly understood that I do not confine myself to the specific details of construction and arrangement herein shown.

75 The operation of my invention is as follows: A supply of steam from any suitable source as from the boiler is admitted to pipe H. This supply can be readily and easily regulated by means of the stop-cock or check valve I. The steam passes from pipe H into pipe K, centrally of the length thereof and from thence into the short projecting pipes 80 or stems L and through opening N, blast hood Q and through opening W in the nose of the blast hood on into the furnace or combustion chamber. By locating the T-connection between pipes K and H centrally of the length 85 of the former an equal supply of steam is admitted to each end or arm of said pipe and consequently to each short pipe L, nozzle M and pipe N and to each end of each blast hood Q, thereby securing a steady and uniform blast in each furnace or combustion chamber. By reason of the pipes being open ended and thereby communicating with the outer air, a draft of air is created by the jet 90 of steam issuing from the nozzle M and this 95 jet of steam forces the air into the blast hood Q. Here the air and steam become thoroughly mixed and a slight condensation of the steam is caused by coming in contact with the cooler air. The draft issuing from the blast hood, 100 through the slot or opening W in the nose thereof, and into the furnace or combustion chamber is moisture laden and thus acts as a blanket to prevent the solid or unconsumed 105 particles or products of combustion from being 110 carried off, by the flame in the form of smoke, until they have been thoroughly subjected to the action of the heat and flame and consequently thoroughly and effectually consumed. This action, taking place in the combustion 115 chamber itself avoids the necessity of conducting the smoke containing the unconsumed 120 particles of the product of combustion to an auxiliary furnace to be consumed and thus is produced an extremely simple and convenient 125 arrangement whereby such consumption is effectually and easily secured. The blast of steam moistened air issuing from the mouth 130 W of the blast hood is directed downwardly in an inclined direction, and strikes the bridge wall a short distance above the rear ends of the grate bars. This blast traverses the mass of flame arising from the fuel and while the flame is not arrested by the blast, the unconsumed particles are arrested and held in the 135 flame until they have been consumed or else they are forced by the blast back to the bridge wall, thus passing over the bed of heated and burning fuel. The bridge wall against which

the blast impinges, acts as a deflector to return such particles as are not consumed in the passage rearwardly over the fuel bed, back or forwardly over the burning fuel and 5 by reason of the inclined direction of the draft from its point of entrance to the point it strikes the bridge wall is brought in closer contact with the heat and thereby the solid or unconsumed particles are thoroughly and 10 effectively consumed. The beveled portion U of the blast hood and the pivoting of said hood upon its elbow supports forms an important and valuable feature of my invention for thereby I am enabled to secure a steady 15 rest for the blast hood in its setting, and at the same time provide angular adjustment of the same so as to regulate and adjust the path of the blast in the furnace chamber by filing the beveled face U as occasion may require. 20 It will be observed that the mouth of the blast hood opening into the furnace is flared. The object of this construction is to permit the blast issuing therefrom to reach every part of the furnace chamber, for if said mouth 25 were straight, a part of said chamber would not be reached by the blast, as will be readily understood by reference to Fig. 2, and consequently the effectiveness of the apparatus would be seriously impaired. 30 Having now fully described my invention and explained the principles thereof and the best mode in which I prefer to apply these principles, what I claim as new, and desire to secure by Letters Patent of the United States, 35 is—

1. In a smoke consumer a blast hood adapted to receive a blast of air and steam and to deliver the same into a combustion chamber, said blast hood being beveled upon the lower 40 side thereof whereby a solid bearing support is secured therefor, as and for the purpose set forth.

2. In a smoke consumer a blast hood having swivel supports and beveled upon the lower face thereof whereby it may be angularly adjusted, and solidly supported in its angular adjustments, as and for the purpose set forth. 45

3. In a smoke consumer an inclined or tilted blast hood communicating with a furnace chamber, so as to deliver an inclined blast therein, and having an inclined or beveled lower face, in combination with air and steam pipes upon which said blast hood is 50 mounted to be angularly adjusted; substantially as and for the purpose described.

4. In a smoke consumer elbow pipes communicating at one end with the open air, a blast hood swiveled upon the other end of 55 said open ended elbow, air pipes, a system of steam pipes communicating with a source of steam, nozzles projecting from said steam

pipes into the open ends of the elbow pipes and suitable openings between the blast hood and combustion chamber of a furnace, as and for the purpose described. 65

5. In a smoke consumer elbow pipes communicating at one end with the open air, a blast hood swiveled upon the other end thereof, said hood having a beveled face and capable of angular adjustment upon its swivel supports, and communicating with the interior of a furnace chamber steam jets projected into the open ends of the elbow pipes and a system of steam pipes for supplying steam to said jets from any suitable source; substantially as described and for the purpose set forth. 70

6. In a smoke consumer a steam supply pipe, a delivery pipe, a T-connection between 80 said supply and delivery pipes centrally of the length of the latter, a pair of steam jets connecting with the delivery pipe on each side of the T-connection, elbow pipes or tubes communicating with the air, said jets projecting into the open ends of said elbow pipes or tubes, a blast hood adjustably swiveled on the other ends of said elbow tubes or pipes and communicating with the same and also with the interior of a furnace chamber, all 85 combined, arranged and operating substantially as and for the purpose set forth. 90

7. In a smoke consumer, an oblong casing forming a blast hood, two faces of said hood beveled to form a nose piece, a flaring mouth 95 in said nose piece communicating with the interior of said hood and opening into a furnace chamber and suitable air and steam inlets in the ends of said casing or blast hood; as and for the purpose set forth. 100

8. In a smoke consumer, a blast hood located in a boiler setting or framework above and in proximity to the furnace door, said hood being tilted or inclined and communicating with the interior of said furnace chamber so as to deliver an inclined blast therein to impinge on the bridge wall a short distance above the rear ends of the grate bars open ended tubes or elbow pipes also located in the boiler setting and communicating with the interior of the blast hood and also the open air, and upon which the blast hood is adjustably swiveled, steam jets projected into the open ends of said elbow pipes or tubes and a system of pipes delivering steam from 105 any suitable source to said jets; all combined, arranged and operating as and for the purpose set forth. 110

In testimony whereof I have hereunto set my hand in the presence of two witnesses.

FRANK S. SEJNOHA.

In presence of—

CHARLES SHENOHA,
DAVID TRANK.
